VESSEL AND FLUID PROPELLED DEVICE
Homer J. Shafer, Mansfield, Ohio.
Application July 11, 1952, Serial No. 298,418.
8 Claims. (Cl. 103—80).

This invention relates to propelling devices and is more particularly directed to a mechanism involving a plurality of either rigid or flexible fins arranged to operate in a timed relation for moving a liquid through a suitable conduit or a body through or over water.

The object of this invention is to produce a propelling device for liquids or for a vessel or other liquid suspended body.

The invention consists in the provision of serially arranged fins oscillatably mounted in a suitable body suspended or submerged in a liquid, each fin adapted to be driven so that the succeeding fin is out of phase therewith to thereby propel liquid through a conduit or the vessel in which the fins are mounted through or over the liquid in which the vessel floats or is suspended.

In the drawings:

Fig. 1 is a longitudinal sectional view of a propelling device embodying the invention;

Fig. 2 is a schematic plan view of the device shown in Fig. 1;

Fig. 3 is a sectional view, partly in plan, embodying a modification of the invention;

Fig. 4 is a side elevational view, partly in section, of the device shown in Fig. 3; and

Fig. 5 is a plan view showing another modification of the invention showing different drive mechanism for the propelling fins.

This application is a continuation in part of previous application Serial Number 693,672, filed August 29, 1946, and entitled Vessel and Fluid Propelling Device, on which Patent No. 2,611,321 was issued September 23, 1952.

The invention is disclosed in the several figures, of the drawings in which the numeral 1 designates a suitable body made up in the form of a tubular member that may be submerged in a liquid by itself or may be secured to a vessel to be propelled through water or may be installed in a liquid conducting conduit through which liquid is to be forced. The basic principle of operation is the same regardless of whether the tubular member is moved or the liquid is moved through the tubular member.

A plurality of spindles 2, each rotatably, or preferably oscillatably mounted in the body 1, suitable bearings being provided in which the spindles are rotatably or oscillatably mounted. An impelling unit or member 3, sometimes referred to as a fin, is secured to each of the spindles 2 by means of a clamp 4. Each impeller is preferably made of spring sheet material. The impellers or fins may be made of uniform section material or they may be of tapered section, i. e. having a section at the clamp end thicker than that at the trailing or opposite end thereof. The function of the varying section is to increase the propelling action by increasing the whipping action of the impellers or fins. The use of rigid fins or impellers is contemplated and the whipping action is quite similar and also occurs in flexible uniform section impellers or fins, the whipping action being of lesser intensity. The tapered flexible fin will move more fluid relative to the body than

uniform section fins or impellers either flexible or rigid. While the impellers are shown operating in a tubular body it may be omitted when the impellers are intended to move a vessel through or over water although the operation may not be as efficient as when mounted in body 1.

Suitable power means are applied to each of the spindles 2 for operating them in timed sequence. The preferred sequence is illustrated in Fig. 2 wherein the relative position of each fin or impeller relative to its adjacent one is shown.

The action of the impelling units is such that pressure is built up on one side of the fin as it advances into the liquid and a subatmospheric pressure is built up on the opposite side thereof. The succeeding fin has a pressure and subatmospheric pressure built up on opposite faces or sides of the impeller in the same manner and so on for each succeeding fin. As the impellers are oscillated from side to side the impellers will have the pressure and subatmospheric pressure applied to alternate sides thereof during each cycle of operation. Relative movement will then be imposed on the liquid or fluid relative to the tubular body to cause movement in either the liquid or vessel to which it is secured or in which the spindles are oscillatably mounted. A diagrammatic illustration of the pressures and subatmospheric pressures is shown in the application of which this is a continuation and to which reference is hereby made.

The above description applies to impellers or fins made of spring or flexible material of either uniform or tapered section. A rigid or non-flexible material will operate in the same manner although the effectiveness and efficiency may vary somewhat from that of the spring like or resilient impeller members.

Figs. 3 and 4 illustrate one mechanism for operating two or more impellers in the necessary timed sequence. This comprises a pair of cranks 5 and 6 mounted for rotation in tubular body 7. The cranks are secured to suitable spindles journaled in the tubular body. The impellers or fins 8 and 9 are secured to spindles 10 rotatably mounted in the tubular body 7 and fixed to each spindle is a lever arm 11, each arm being suitably pivotally secured to a jointed crank bar or pitman 12 connected to pin 13 fixed to crank 5.

Impellers or fins 14 and 15 are secured to spindles 16 and 17 rotatably mounted in the body 7. Each of these spindles has a lever arm 18 fixed thereto that is suitably secured to a jointed crank bar or pitman 19 connected to pin 20 secured to the crank 6. The movement of the bars 12 and 19 rotates or swings the spindles 10 and 15 and the spindles 16 and 17. These spindles are alternately arranged and operate in the correct timed or phased relationship. The length of the lever arms 18 and 11 determines the extent or sweep of the impellers and the rotational position of the crank pins 13 and 20 determines the phase relationship of the impellers operated by the cranks 5 and 6. As shown in Fig. 3, the lever arms 18 are longer than arms 11 so that the sweep of impellers 14 and 15 is shorter and somewhat slower than impellers 8 and 9. A drive gear 21 is disposed between cranks 5 and 6 for driving them simultaneously so that the proper phase relationship of the impellers or fins will remain constant.

Another form of drive is shown in Fig. 5 wherein the tubular body is omitted although it is employed in actual practice and all claims calling for a tubular body are to be construed as readable thereon. The propelling device comprises a bar 22 having arms 23 pivotally connected thereto and spaced along the length thereof. Each arm has a spindle 24 secured thereto that is rotatably supported in the vessel to be propelled or in the tubular body through which liquid is to be moved. A fin or

impeller 25 is secured to each spindle and may be rigid or flexible and of uniform or varying section. A second bar 26 is provided that is substantially parallel to the bar 22 and has arms 27 pivotally connected thereto. Each arm is spaced along the length of bar 26 and is spaced alternately to the arms 23. The arms 27 are secured to spindles 28 rotatably mounted in the vessel or tubular body. Fins 29 similar to fins 25 are secured to the spindles 28. Each of the bars 22 and 26 is actuated by a double acting fluid motor 30. Suitable jointly operable reversing valves (not shown) are provided for causing pistons 31 and 32 to reciprocate in a predetermined phase relationship similar to that shown in Fig. 3. The piston rods 33 and 34 are pivotally connected to the bars 22 and 26 respectively. The mode of operation of this device is identical to that shown in Fig. 3.

That which is regarded new, novel and useful and which is sought to be protected by Letters Patent of the United States is as follows:

1. A liquid pumping and propelling device comprising a body member, a plurality of spindles oscillatably mounted therein and spaced along the length of the body member, a fin connected at one end to each spindle, means connected to every alternate spindle for oscillating same, a second means connected to the other alternate spindles for oscillating same, and means for actuating said connecting means in timed sequence so that fins on succeeding spindles are oscillated in a predetermined phase relationship.

2. A liquid pumping and propelling device comprising a body member, a plurality of spindles oscillatably mounted in said body member and spaced along the length thereof, a fin connected to each spindle, an arm connected at one end to each spindle, alternate arms extending laterally in opposite directions, a bar pivotally connected to the other ends of every alternate arm, a second bar pivotally connected to the other ends of the arms on the other alternate spindles, and means for reciprocating said bars for oscillating said spindles and fins in a predetermined phase relationship.

3. A liquid pumping and propelling device comprising a tubular body member, a plurality of spindles oscillatably mounted in said body member and uniformly spaced along the length thereof, a fin connected to each spindle, an arm connected at one end to each spindle, alternate arms extending laterally in opposite directions, a bar connected to every alternate arm, a second bar connected to the arms of the other alternate spindles, a crank for reciprocating one of said bars and the spindles connected thereto, a second crank for reciprocating the other of said bars and the spindles connected thereto, and means for jointly rotating said cranks in a predetermined phase relationship.

4. A liquid pumping and propelling device comprising a tubular body member, a plurality of spindles oscillatably mounted in said body member, said spindles uniformly spaced along the length of the body member, a fin connected to each spindle, an arm connected to each spindle and extending laterally therefrom, a bar connected to every alternate arm, a second bar connected to the other alternate arms, a fluid motor connected to one of said bars, a fluid motor connected to the other of said bars, and the second motor to be actuated in and out of phase relation to the first mentioned bar.

5. A liquid pumping and propelling device comprising a tubular body member, a plurality of spindles oscillatably mounted in said body member and uniformly spaced along the length of the body member, a rigid fin secured to each spindle, an arm connected to each spindle and extending laterally therefrom, a bar connected to every alternate arm, a second bar connected to the other alternate arms, and means for reciprocating said bars and spindles in a phase relationship with respect to each other.

6. A liquid pumping and propelling device comprising a tubular body member, a plurality of oscillatable spindles mounted in said body member and uniformly spaced along the length thereof, a flexible fin secured to each spindle, an arm connected to each spindle and extending laterally therefrom, a bar connected to every alternate arm, a second bar connected to the other alternate arms, and means for reciprocating said bars, spindles and fins in a predetermined phase relationship.

7. A device as defined in claim 6 in which said fin has a body section tapered in thickness from its leading end to a thinner trailing end.

8. A liquid propelling device comprising a body member, a pair of oscillatable spindles mounted in the body and spaced apart in substantial alignment, a fin connected at one end to each spindle, means connected to one spindle for oscillating said spindle over a predetermined stroke at a predetermined speed, and means connected to the other spindle for oscillating said other spindle over a different stroke in timed relation to said one spindle.
